Patented Nov. 5, 1957

181,338

GOLF BALL TEE

Wendell K. Beckwith, Whitewater, Wis., assignor to New Products, Inc., a corporation of Wisconsin

Application May 15, 1957, Serial No. 46,186

Term of patent 3½ years

(Cl. D34—5)

FIG. 2.

FIG. 1.

FIG. 3.

Fig. 1 is a side elevation of a golf ball tee embodying my new design;

Fig. 2 is a top view of the golf ball tee; and

Fig. 3 is a bottom view of the same golf ball tee.

I claim:

The ornamental design for a golf ball tee, substantially as shown.
